PLASTIC JUG

Norman A. Kelly, Wayne Township, Kosciusko County, Ind., assignor to Crystal Preforming and Packaging, Inc., Warsaw, Ind., a corporation of Indiana

Filed June 30, 1966, Ser. No. 2,876

Term of patent 14 years

(Cl. D58—5)

FIGURE 3 is an elevational view of one side thereof, the other side being substantially the same; and

I claim:

The ornamental design for a plastic jug, as shown and described.
